UNITED STATES PATENT OFFICE.

JOSEPH DOVE-SMITH, OF NIAGARA FALLS, ONTARIO, CANADA.

BOX-LABELING MACHINE.

1,158,650.

Specification of Letters Patent.

Patented Nov. 2, 1915.

Application filed November 5, 1913. Serial No. 799,299.

To all whom it may concern:

Be it known that I, JOSEPH DOVE-SMITH, a citizen of the Dominion of Canada, residing at Niagara Falls, in the county of Welland and Province of Ontario, Dominion of Canada, have invented new and useful Improvements in Box-Labeling Machines, of which the following is a specification.

My invention relates to improvements in box labeling machines, and more particularly to improvements in means for affixing labels or coverings to the tops or faces of paper or pasteboard boxes. It is, furthermore, a part of the invention generally shown and described in my application Serial No. 724,833, filed October 9, 1912, for box making machines, but not therein separately claimed.

It is well known in the art of box making, especially in the manufacture of small boxes, that, first, the high speed of operation required renders it difficult to press down and securely affix labels to boxes; and, second, that where the box surface is curved—either convexed or concaved—the operation is more difficult; and, third, that where the label is embossed or otherwise subject to abrasion by impact of a presser, the operation is still more difficult.

The object of my invention is, therefore, to overcome these difficulties in the manner which will be understood from the following specification and reference to the annexed drawings in which,—

Figure 1 is a plan view of a machine embodying my invention. Fig. 2 is a transverse, vertical, central section of the machine, details and parts unnecessary to an understanding of my present invention being omitted. Fig. 3 is a detail central section of one of my label affixing devices drawn on a larger scale. Fig. 4 is an underside view of my pneumatic presser. Fig. 5 is a detail section of a box holding device and plunger.

It will be seen that these figures correspond generally with Figs. 1, 3, 13, 14 and 7, respectively, of said application Serial No. 724,833, and that the reference characters correspond generally with that application, to which reference may be had for a more detailed understanding of the machine.

I will first describe a cycle of operations

generally, and then describe more specifically the invention herein claimed.

A rotor 1 is mounted to revolve step-by-step upon a fixed table 2, and is driven by a Geneva wheel 3 secured to the under side of the rotor, and a cam-crank 4 on a shaft 5 driven by bevel-gears 6 and 7 from a shaft 8.

Boxes, or box covers, or box bottoms are stacked in the magazine 22 by an operative, and the boxes are fed into the box holders on the rotor by any desired mechanism.

The box holder, as clearly shown in Fig. 5, holds the box upon its ends, or sides as the case may be. The rotor has the upwardly-extending cylindrical portions 45, each of which carries within it a plunger 29. To each of these cylindrical portions is clamped a box holder of the following construction. Each clamp 46 has upwardly-turned end-plates 47. Reciprocatingly secured by pins 48 in slots in these end-plates are plates 49. These plates 49 have internal flanges 50, upon which rest out-turned flanges 51 on plates 52 which are rigidly secured to the plungers 29. Hinged to the plates 49 are plates 53. These plates 53 have cylindrically-formed beads 54 formed upon their upper edges which bear against the outsides (ends or sides as the case may be) of the boxes when in place. Light springs 60 hold the plates 53 up against the boxes. The convexed heads of the plungers 29 are of a size to move freely in and out of the boxes without contacting the inner walls. Projecting inwardly on the plates 49 and adjacent to the hinges are shoulders 61 which lie above and in the path of the flanges 51 on the plates 52. Threaded into the bottoms of the plates 49 are pins 62 having heads 63, which heads slide within tubular sleeves 64 which are rigidly secured to the clamps 46. Within the sleeves 64 and bearing against the heads 63 and the clamps 46 are compression-springs 65. When a box has been shoved to place between the beads 54, it is held firmly against any horizontal movement. When the rotor is moved bringing the box holder to any one of the operative positions, the plunger 29, raised by a follower, enters the interior of the box, and the flanges 51 contact with the shoulders 61 on the plates 49, thus lifting the plates

49, the clamping or holding parts and the box carried thereby up against the overhanging fixed member, between which and the plunger the box receives the desired treatment.

5 Assuming a box to have been put in place upon one of the box holders and assuming that the box is to be domed or convexed, the Geneva wheel moves the rotor one step and 10 brings the box to position for the domer to act. Following this action the box is moved one step to the position for application of glue or paste to its surface. This done, the Geneva wheel moves it to position where 15 a label is made to adhere to the glue-covered surface. The rotor next moves the box to the pressing or affixing mechanism which is hereafter more fully described. In order to secure perfect contact and smoothness, I 20 prefer to subject the label to the action of a second affixing mechanism identical with the one presently described. The rotor now moves the box into position to be ejected. This is accomplished by a pneumatic device 25 which blows the box out of the box holder, as fully described in my aforesaid application.

I will now describe particularly the invention herein claimed.

30 Mounted over the line of travel of the plungers 29 is a plate 88, which is rigidly supported upon the table 2 and the central plate 66. Secured to a projection upon the under side of this plate is a rubber or other 35 resilient pad 38 which is of a size to substantially cover the label. This pad 38 has a rectangular slot 89, clearly shown in Fig. 4, and within the boundaries of this slot the surface of the pad is a trifle above the surface external thereto (it being understood that I am now describing a construction particularly adapted to domed boxes). This forms a sort of air chamber within the portion of the pad bounded by the slot 89, and 40 also causes the pad to conform more closely to the convex surface of the box. Leading into this rectangular slot are air openings or apertures 90. These air openings connect with a central air-valve 91, the head of 45 which is in an air supply chamber 92. A supply of air under pressure is carried to this chamber, as by a coupling 93, shown in Fig. 3. The bottom of the stem of this valve, when the valve is in the closed position, lies below the pressing surface of the pad 38, so that, when a plunger 29 raises a 50 box and adhering label into contact therewith, it will press the stem of said valve upwardly, open the valve, and permit air 55 under pressure to pass through the openings 90 into the rectangular slot 89, to spread out over the central portion of the label, and be forced out over the edges of the label to smooth it and press it down. The down- 60 ward movement of the plunger 29 will per-

mit the springs 65 to carry the box with the affixed label down and out of contact with the stem of the valve, which valve will then close automatically and shut off the air.

As a matter of fact, the actual physical contact of the pad 38 with a label is very slight, and the cushioning effect of the air is such that a most delicately embossed label is uniformly pressed down and in no wise abraded or marred by contact with the pad. 75 And as the action of the machine must be exceedingly rapid, the application of affixing pressure is much more rapid and much more uniform than can be attained by the use of a pressure pad. As stated, I preferably repeat this action by the use of a second, identical presser. Both of these pressers may be supplied with air from a pipe 94 provided with a T 95, which source of air supply also actuates the ejector at the 80 next step of the rotor. The form of the pad above described, with proper change in length of the valve stem, may be adapted with equal efficiency to affixing labels to boxes having plane or concaved surfaces. 90

Having thus described my invention, I claim:—

1. In combination with a rotor, plungers and means for actuating the same and a box-holding device carried by said rotor, a 95 pressing mechanism comprising a pressing pad, openings therein connecting with a supply of compressed air through a valve, a source of compressed air supply, a valve, a stem on said valve extending below the 100 plane of the surface of said pressing pad, whereby said valve is opened by the contact of a box bearing a label by the upward movement of the plunger and air pressure is applied to the label to smooth and compress 105 the label at the time pressure is applied.

2. In combination with a rotor and box-carrying devices thereon, a label affixing device comprising a pad rigidly mounted over the path of travel of said box-carrying devices and means for forcing a box and superposed label into contact with said pad. 110

3. In combination with a rotor, box-carrying devices thereon mounted to reciprocate vertically, means for effecting such reciprocation, a label affixing device comprising a pad rigidly mounted over the path of travel of said box-carrying devices and means for forcing a box and superposed label into contact with said pad. 115

4. In combination with a rotor and box-carrying devices thereon, a label affixing device comprising a pad having an area for the admission of compressed air, a source of supply of compressed air, a valve for admitting compressed air to said area and means for actuating said valve. 125

5. In combination with a rotor, box-carrying devices thereon mounted to reciprocate vertically, means for effecting such re- 130

ciprocation, a label affixing device comprising a pad having an area for the admission of compressed air, a source of supply of compressed air, a valve for admitting compressed air to said area and means for actuating said valve.

5 Copies of this patent may be obtained for five cents each, by addressing the "Commissioner of Patents, Washington, D. C."

In testimony whereof I have hereunto set my hand in the presence of two witnesses.

JOSEPH DOVE-SMITH.
